DISPENSER FOR ADDING CHEMICALS TO
TOILET FIXTURES OR THE LIKE

Martin A. Johnson, 11633 Hesby St.,
North Hollywood, Calif.

Filed Nov. 5, 1964, Ser. No. 82,495

Term of patent 14 years

(Cl. D16—2)

FIG. 1.

FIG. 2.

FIG. 5.

FIG. 3.

FIG. 6.

FIG. 4.

FIG. 1 is a perspective view of a dispenser for adding chemicals to toilet fixtures or the like with the fragmentary broken line illustration of the pipe being shown for illustrative purposes only.

FIGURE 2, a plan view of the dispenser of FIGURE 1 as it appears uninstalled;

FIGURE 3, a side elevational view of the dispenser of FIGURE 2;

FIGURE 4, a bottom view of the dispenser of FIGURE 2;

FIGURE 5, a rear elevational view of the dispenser of FIGURE 2; and

FIGURE 6, a front elevational view of the dispenser of FIGURE 2.

The dominant features of the design reside in the portions shown in full lines.

I claim:

The ornamental design for a dispenser for adding chemicals to toilet fixtures or the like, as shown and described.
